Patented Aug. 18, 1914.

UNITED STATES PATENT OFFICE.

AUGUST HELLMUTH AND SEBASTIAN MAULBECK, OF WEST HOBOKEN, NEW JERSEY.

CONTROLLING APPARATUS FOR SEWAGE-DISPOSAL PLANTS.

1,107,788.

Specification of Letters Patent. Patented Aug. 18, 1914.

Application filed September 24, 1913. Serial No. 791,502.

To all whom it may concern:

Be it known that we, AUGUST HELLMUTH and SEBASTIAN MAULBECK, citizens of Germany and the United States, respectively, 5 and residents of West Hoboken, county of Hudson, and State of New Jersey, have jointly invented a new and useful Controlling Apparatus for Sewage-Disposal Plants, of which the following is a specification.

10 This invention relates to a device of novel construction, designed more particularly to normally lead the sewage into depositing troughs of suitable construction, while upon an excessive flooding of the sewer, the sewage is cut off from such troughs and caused to run off unhindered. As soon as the normal liquid level in the sewer has been re-established the sewage is again automatically admitted to the troughs.

20 In the accompanying drawing: Figure 1 is a sectional plan of a sewage controlling apparatus embodying our invention; Fig. 2 a cross section on line 7—7, Fig. 1; Fig. 3 a vertical section on line 8—8, Fig. 1; Fig. 25 4 a section on line 9—9, Fig. 1, and Fig. 5 a detail of the gate guiding means.

It is preferred to arrange one of a pair of depositing troughs A at each side of the main sewer 39 near the discharge end thereof. Across the sewer extends a weir 40 in front of which branches 41 lead from the sewer to the troughs, and through which, under normal conditions, the sewage is by the weir diverted into said troughs. Each 35 branch 41 is controlled by a gate 42 guided

by rollers 43 along upright tapering rails 44. Gate 42 is by rope 45 running over idlers 46 connected to a pocket 47 having a perforated bottom 48, and adapted to be charged with the sewage from a spout 49 whenever the water rises to a level above the top of the weir. In this way, the pocket 47 will be filled with water until it overbalances gate 42 and causes the same to close its branch 41.

45 Thus in case of an excessive rail fall and a consequent flooding of the sewer, the water is excluded from troughs A and caused to run off directly over the weir. Upon a subsequent decrease of the water level, the water 50 will cease to be discharged into pockets 47 and the latter will become emptied through their perforated bottoms, until the gates again overbalance the pockets and will thus open.

55 We claim:

A device of the character described, comprising a sewer, a sludge trough, a branch intermediate sewer and trough, a weir within the sewer at a point beyond the branch, 60 a gate controlling said branch, a perforated pocket operatively connected to the gate, and means for discharging the sewage from the sewer into said pocket.

AUGUST HELLMUTH.
SEBASTIAN MAULBECK.
